United States Patent Office.

F. L. MORRISON, OF NEW ALBANY, INDIANA.

Letters Patent No. 91,959, dated June 29, 1869.

IMPROVEMENT IN HAY-FORK

The Schedule referred to in these Letters Patent and making part of the same.

To all whom it may concern:

Be it known that I, F. L. MORRISON, of New Albany, in the county of Floyd, and State of Indiana, have invented a new and improved Hay-Fork; and I do hereby declare that the following is a full, clear, and exact description thereof, which will enable others skilled in the art to make and use the same, reference being had to the accompanying drawing, forming part of this specification, in which—

Figure 1 represents a perspective view of my improved hay-fork.

Figure 2 is a detail horizontal section of the same.

Figure 3 is a detail section of the jointed prong.

Figure 4 is a detail plan view of the removable prongs.

Figures 5 and 6 are detail side views of the jointed prong.

Similar letters of reference indicate corresponding parts.

This invention relates to a new hand hay-fork, which is so constructed that it can be used to convey a load of hay from places where it is inconvenient to employ other conveying-apparatus.

The invention consists, first, in arranging an adjustable shoulder-rest on the handle of the fork, which allows it to be carried on the shoulder of a man, with a heavy load on its prongs.

The invention consists, also, in the application of a jointed removable prong, which can be swung up to retain a large load upon the fork.

A, in the drawing, represents the handle of my improved hay-fork.

B B are the two main prongs, which are secured in suitable manner to the handle, and which, if used alone, allow the device to be employed as a manure-fork.

Between the prongs B B, is formed a socket, to receive either a single third prong, C, or a double or treble prong, D, which additional prongs are held with their shanks a in the said socket, by a suitable spring-catch, b.

The single prong C is jointed, its main fixed part c being about as long as or longer than the prongs B,

while its front part d is pivoted to the front end of c by a pin, e, as in fig. 3. The said pin e passes through a slot of the part c.

A hook, f, is formed on the front end of the part c, to lock the part d in the turned-up position, for which purpose, also, a spring may be provided.

When the fork is to be filled, its prong C is straightened, as in fig. 5, and pushed into the hay or straw up to the handle. The handle is then pressed down and swung up, whereby the part d will be retained horizontally on the ground, and locked, by the hook f, in the position shown in fig. 6.

The fork can then, full of hay, manure, or straw, be conveyed from one place to another, the part d of the prong C holding the hay in place. Two or more such jointed prongs C may be used on one fork.

E is a short bar or plate, which is perforated, so that it can be fitted upon the handle, and adjusted thereon in any desired position. It can be locked by means of a screw, g, or otherwise, in any desired position.

This bar or plate E is made of wood, metal, or other desired material, and serves as a shoulder-rest to support the fork on the shoulder of a man. The load is thereby considerably reduced, and can be conveniently carried any desired distance.

Having thus described my invention,

What I claim as new, and desire to secure by Letters Patent, is—

1. The adjustable shoulder-rest E, arranged on the handle of a fork, substantially as and for the purpose herein shown and described.

2. The jointed prong B, consisting of the parts b c, when arranged on a hand-fork, to operate substantially as herein shown and described.

3. The hand hay-fork, consisting of the handle A, fixed prongs B, detachable prongs C or D, which may be jointed, as described, all made and operating substantially as herein shown and described.

F. L. MORRISON.
